CURT L. E. MUELLER, OF JOLIET, ILLINOIS, ASSIGNOR TO THE CHALLENGE SPARK PLUG COMPANY, OF JOLIET, ILLINOIS, A CORPORATION OF ILLINOIS.

SPARK-PLUG.

1,326,606.

Specification of Letters Patent. Patented Dec. 30, 1919.

Application filed July 14, 1917. Serial No. 180,536.

To all whom it may concern:

Be it known that I, CURT L. E. MUELLER, a citizen of the United States, residing at Joliet, in the county of Will and State of Illinois, have invented a new and useful Improvement in Spark-Plugs, of which the following is a specification.

My invention relates more particularly to improvement in spark-plugs used in internal 10 combustion engines for igniting the charges for driving the engine.

My primary objects are to provide a spark-plug of such construction that upon each suction stroke of the engine air will 15 be drawn into the cylinders above the pistons therein, through the spark-plug, preferably to perform the double function of driving from the upper end of the cylinder above the piston therein when at the limit 20 of its upward stroke and from the interior of the spark-plug, burnt gases, which, if allowed to accumulate, especially during the successive operations of the pistons, result in the formation of carbon deposits on the 25 piston cylinder and the exposed parts of the spark-plug, and seriously impair operation of the engine; another object is to provide for forcing from the inner end of the spark-plug; particles of carbon which may have 30 become deposited thereon; another object is to still further provide against the accumulation of carbon in the spark-plug, by agitation of one of the electrodes of the plug; another object is to provide improved 35 means whereby the operator may readily determine whether or not the ignition circuit is dead or is short-circuited, and to provide for the intensification of the ignition spark; and other objects as will appear from 40 the following description:

Referring to the accompany drawing—

Figure 1 is a view in vertical sectional elevation of a spark-plug constructed in accordance with my invention and provided with spark-intensifying means and short-circuit detecting means in accordance with my invention; Fig. 2 is a section taken at the line 2 on Fig. 1 and viewed in the direction of the arrow; Fig. 3 is a broken section taken at the line 3 on Fig. 1 and viewed in the direction of the arrow; and Fig. 4, a view in elevation, partly sectional,

of a modification of one of the electrodes of the plug.

Referring to the construction illustrated in Figs. 1, 2 and 3, 5 represents the usual metal shell adapted to be screwed at its threaded portion 6 into the spark-plug opening of a cylinder above the piston 60 therein, the lower, inner end of this shell being provided with an electrode 7, which is in electrical connection with the shell 5, commonly grounded through its connection with the cylinder of the engine. Extending 65 into the shell 5 and resting against a seat 8 therein, having a soft metal facing 9, is a member 10 of porcelain or other material non-conductive of electric current, this member 10 being held rigidly to the shell 5 by 70 means of a plug 11 surrounding the member 10 and screwing into the upper threaded end of the shell 5. The member 10 contains a bore 12 extending longitudinally therethrough at its central portion, with an enlargement 13 at its lower end forming with the portion 12 a shoulder 14. A metal tube 15 is located in the bore 12, this tube interlocking at its headed portion 16, which is disposed in the portion 13 of the bore 12, 80 and extending at its upper threaded end 17 through the upper end of the member 10. Surmounting the member 10 and screwed upon the portion 17 of the tube 15, is a pair of metal nuts 18 and 19, the nut 18 serving 85 to hold the tube 15 and member 10 in assembled relation and these two nuts, in the case of the particular construction illustrated, serving to clamp to the spark-plug a spark-intensifying and short-circuit 90 detecting device hereinafter referred to, but which when this device is not used, may serve as a binding post for connection with one of the terminals of the sparking circuit, the other being grounded on the engine and 95 thus in electrical connection with the electrode 7. The other electrode of the spark-plug is represented at 20, this electrode extending at its lower end into close proximity to the electrode 7, in accordance with common practice. In the particular construction now being described this electrode, which may be of any suitable current-conducting material, extends upwardly through the passage 21 extending through the tube 15, 100 the member 20 being of such diameter rela-

2
tive to the diameter of the passage 21 that desirable clearance between these parts for the passage of air downwardly through the tube 15, as hereinafter described, may be effected.

Surmounting the nut 19 is an inwardly opening valve device 22, formed of a casing 23, which is screwed upon the threaded reduced portion 24 of the nut 19 and contains 10 a valve-seat 25, and a valve proper 26 co-operating with said seat and extending at its stem 27 through a washer 28, between which and a wall 29 of the valve casing in which the seat 25 is located, a coil-spring 30, screwing upon the upper end of the stem 27, is free to slide in the valve casing and thus 15 rounding the stem 27, is confined. The washer 28, which contains openings 32, and is held on the stem 27 by means of a nut 31 screwing upon the upper end of the stem 27, is free to slide in the valve casing and thus 20 the spring 30 tends to seat the valve 26. The electrode member 20 in this construction is rigidly connected with the valve proper 26, as by securing it at its upper end in a socket 33 in this valve, and thus is in electrical connection with the member 19.

In the operation of the engine equipped with the spark-plug, the suction produced in the cylinder of the engine upon its suction stroke, causes suction to be exerted upon the 30 valve-equipped passage in the spark-plug and causes air to flow from the atmosphere through the valve-casing 23, passage 21 and into the cylinder of the engine, the valve 26 automatically opening in this operation, and 35 the electrode 20 lowering with the valve, the valve 26 immediately closing as soon as the suction action ceases in the cylinder. It will thus be understood that each time the engine moves on its suction stroke air will be drawn 40 into the cylinder above the piston, through the spark-plug, with the result of displacing the burnt gases in the lower end of the spark-plug and in the upper end of the cylinder resulting from previous explosions, 45 thus minimizing the accumulation of carbon in the spark-plug and the upper end of the cylinder, and cooling the lower end of the spark-plug to prevent premature ignition; and further avoiding objectionable accumulation of carbon in the spark-plug by the reciprocal movement of the electrode 20, which tends to break up carbon deposits in 50 the plug.

The spark-intensifying and short-circuit detecting device hereinbefore referred to is 55 represented at 34, and is constructed as follows: It is formed of a tube 35 of insulating material encircled by a strap 36 of current conducting material, the ends 37 of 60 which are clamped between the nuts 18, 19, the tube 17 extending through openings in the ends of this strap. The strap 36 has screwed therein a screw-pin 38, which extends into a radially disposed socket 39 in 65 the member 35. The member 35 is provided

at one end with a binding post 40, which extends at its threaded portion 41 partway into the member 35, as shown. Screwed into the member 35 from the opposite end thereof to extend into alignment with the post 41 is a 70 threaded rod 42 provided with a hand-grip 43, this rod being disposed centrally of the member 35 and being adapted to be screwed to a position in the member 35 in which it contacts with the binding post 41. 75

The terminal of the sparking circuit other than the one which is grounded would be connected with the binding post 40 and thus through the tube 42, pin 38, strap 36 and nuts 18 and 19, electrically connected with the 80 electrode 20, the screw 38 being adjustable in the opening 39 for producing a gap between the rod 42 and this screw, when it is desired to intensify the spark to be produced at the space between the electrodes 7 and 20. 85

In the use of the construction as shown, the current would pass from the binding post 40, thence to the rod 42, which may be adjusted relative to the post 41 to present an intensifying spark-gap, if desirable, thence 90 to the pin 38 across the gap between it and the rod 42, if the adjustment is such as to produce such a gap and intensification of the spark is desired, thence through the sleeve 36, nut 19, valve device 22, electrode 20, 95 across the spark-gap between this electrode and the electrode 7 to the shell 5, where it is grounded and connects with the other grounded terminal of the sparking circuit.

By adjusting the member 42 away from 100 the binding post 41, the operator may readily determine, first, whether or not any current is passing through the spark-plug, and, secondly, whether or not the spark-plug is 105 short-circuited. This may be determined by observing whether or not the spark will jump a predetermined gap between the binding post 41 and the rod 42. To simplify this observation, I prefer to provide two openings, 44 and 45, extending diametrically through the member 35 and so positioned 110 that when the operator rotates the rod 42 to a position in which its extremity, which opposes the binding post 41, is exposed to view in the opening 44, the gap between the post 41 and rod 42 would be of such length that if the normal amount of current is being supplied to the plug, regardless of short-circuit in the plug, the current would jump this 115 gap and would indicate that current is passing through the plug; and when this rod is adjusted to a position in which its said extremity is exposed to view through the opening 45, this gap will be of such length that the current will not jump it unless the spark-plug is short-circuited. 120

It will be understood from the foregoing that the operator may thus readily determine whether or not current is passing through the spark-plug 125 and whether or not it is short-circuited, and 130

furthermore, he may intensify the spark as desired.

It may be further stated that by the valve mechanism 22, as shown, the nut 31 may be 5 adjusted to regulate the amount of air sucked through the plug and if desired it may be screwed down to such an extent that this valve may be closed if desired. Furthermore the valve casing and passage 10 through the spark-plug also serves as a means of introducing a priming medium into the cylinder of the engine, as for example, for use in starting, the said medium being poured into the upper end of the 15 valve-casing 23, the operator, if desired, depressing the valve 26 to permit of the flow of the medium into the cylinder or this introduction being automatic, if desired, by the suction action of the engine in cranking. 20 If desired the intensification at the pin 38 may be supplemented by a spark-gap produced between the post 41 and the rod 45. Furthermore the manner of connecting the detecting device with the plug permits of 25 the proper positioning of this device about the axis of the plug, to permit of its connection with the sparking terminal regardless of the position to which the plug screws into the cylinder. 30 The construction illustrated in Fig. 4 is the same, except that the electrode 20, instead of being reciprocable and connected with the valve 26, as shown and explained of the preceding construction, is secured to 35 the lower end of the tube 15, as indicated at 46, in which case it would be in electrical connection with the binding post members 18 and 19 through the medium of the tube 15, and the opening 21 in the tube 15 would 40 preferably be smaller than in the case of the preceding construction.

While I have illustrated and described two forms in which my invention may be embodied, I do not wish to be understood

as intending to limit it thereto, as the same 45 may be variously modified and altered without departing from the spirit of my invention, it being my intention to claim my invention as fully and completely as the prior state of the art will permit. 50

What I regard as new and desire to secure by Letters Patent is:

1. A spark-plug containing an air-passage for communication of the interior of the cylinder of an engine equipped therewith, with the atmosphere, and through which air is drawn into the cylinder of the engine upon the suction stroke of the engine, a check valve in the outer end of said passage operating to permit air to be drawn 60 through said passage and into the cylinder, spring means for normally holding said valve closed, and a rod of current-conducting material forming one of the sparking electrodes of the plug, operatively connected 65 with said valve for movement with the latter and extending inwardly from the valve loosely in said passage and reciprocable in the latter with said valve.

2. A spark-plug containing an air-passage for communication of the interior of the cylinder of an engine equipped therewith, with the atmosphere, and through which air is drawn into the cylinder of the engine upon the suction stroke of the engine, a valve in the outer end of said passage operating to permit air to be drawn 70 through said passage and into the cylinder, spring means for normally holding said valve closed, and a rod of current-conducting material forming one of the sparking electrodes of the plug, operatively connected 75 with said valve for movement with the latter and extending inwardly from the valve loosely in said passage and reciprocable in 80 the latter with said valve.

CURT L. E. MUELLER.
